BANK CASHIER'S GUARD

James M. Cordray, Los Angeles, Calif., assignor
of one-half to Mrs. Sachiyō Iwamizu, Los
Angeles, Calif.

Application February 10, 1934, Serial No. 710,709

3 Claims. (Cl. 20—1.01)

This invention relates to protective apparatus for cashiers, clerks and other operatives, in various business institutions, employed at cashiers' windows.

5 It is an object of the present invention to provide an inexpensive, practicable, reliable and quick acting safety apparatus and further to provide such apparatus including means to effectuate the capture of a potential robber in an attempt to hold-up or rob the cashier of available money at the cashier's window.

Further it is an object to provide means to protect the clerks at other windows in the same room in which a cashier at a window is being threatened with robbery.

15 Further it is an object to provide means for rendering an audible and visible signal exterior to the institution being held-up.

Additionally it is an object to provide a safety 20 gate means for a door or doorways of institutions, especially banks, so that escape from the room may be prevented in the event that a robber at a cashier's window has confederates in the banking or other cashiers' rooms.

25 The invention consists in certain advancements in this art as set forth in the ensuing disclosure and having, with the above, additional objects and advantages as hereinafter developed, and whose construction, combination and details of 30 means, and the manner of operation will be made manifest in the description of the herewith illustrative embodiment; it being understood that modifications, variations and adaptations may be resorted to within the scope, principle and spirit 35 of the invention as it is more directly claimed hereinafter.

Figure 1 is an interior elevation of a fragment of a bank room showing an open doorway and one of a plurality of cashiers' windows in the 40 room.

Figure 2 is a vertical section on line 2—2 of Fig. 1, partly in elevation, showing the robber's trap-cage in elevated, concealed position in front of the cashier's counter, and showing safety shutters at the cashiers' windows in open normal position.

45 Figure 3 is a detailed view of a trip device to effect action of a rock-shaft element of the system.

50 Figure 4 is a perspective of an upper shutter of the system.

Figure 5 is an interior face view of a portion of the room wall showing a plurality of cashiers' cages and a vault.

55 In its illustrated embodiment the invention is

shown as incorporated in a bank room 2 having a doorway 3 whose doors 4 are shown in open position. Concealed in the wall of the room and adjacent to the doorway 3 is a slideable trap-door 5 mounted and operative in such a manner as to be quickly thrust across the doorway 3 to closing position. The closing of the door is effected by suitable means preferably under electrical control and depicted as including a spring 6 reacting against a head 7 of a rod 8 which is connected to a lever arm 9, this being pivoted on a fulcrum 10 and at one end connected by a link 11 to the trap-door 5.

Preferably the door is a continuous sheet or panel of substantially bullet-proof material so that persons so inclined may not shoot inwardly or outwardly through the doorway 3.

Control of the trap-door 5 is had by means of a trip latch 12 connected to an armature 13 of an electric coil 14 whose circuit wires 15—16 are 20 connected in parallel with wires 17—18 of an electric circuit having a main control switch 19.

This control switch, of which there is one at each cashier's counter 20, is preferably concealed as in a dummy money box 21. Therefore, under 25 threat by a robber, the cashier would safely close the switch 19 of the circuit 17—18 and therefrom to the trap-door control device 13—14.

The circuit wires 17—18 lead to an electrical control device 22 normally engaging a lug 23 fixed 30 to a box 24 normally concealed in the rear of cabinet work 25 and guided downwardly by vertical run-way stiles 26 provided on the front of the cabinet work at each cashier's window 27. Therefore when the master switch 19 closes the circuit 35 to the control device 22 this would release the elevated trap-box 24 and this being disposed to fall immediately in front of the cashier's window would serve to entrap the potential robber. The lower portion of the trap box 24 is adapted to be 40 latched by the lock bolt 28 and therefore hold the prisoner captive until an authorized person would unlock the bolt 28 by the proper key applicable to the lock 29 thereof. At its upper concealed portion each of the trap-boxes 24 presents 45 at its bottom a frangible panel 30 provided for the purpose of closing the bottom of the trap-box and appearing simply as a ceiling of the cabinet work.

A feature of the invention resides in effecting 50 the discharge of a suitable gas into the trap box 24 in the event it is tripped to entrap a robber. This is effected by means of a gas bomb 31, for instance containing tear gas, fixed in the top of the trap-box 24 and having a breakable connec- 55

tion as cord 32 to a fixed part of the cabinet so that the release of the gas will be accomplished just as the trap-box starts its descent. The discharge of such gas is obviously for the purpose 5 of rendering the potential robber temporarily unable to discharge fire arms through the walls of the box.

For the further protection of the cashier there is provided at each cashier's window a pull-up 10 shutter 33. This is attached as by a flexible connection such as a light cable 34 which extends upwardly and over a guide pulley 35 and extends down to slide 36 operating in a channel or guide 15 37. This slide 36 is adapted to be engaged by the lug 23 when this has passed downwardly to the requisite degree. Upon engagement of the slide 36 by the lug 23 the pull-up shutter 33 is instantly drawn up to a closing position in the window 27 concurrently with the last portion of 20 the movement of the trap-box 24.

As a further security to the clerks at other cashiers' windows in the same bank room there is provided at each window 27 a drop shutter 38 normally held in upper position by a latch 39 to 25 uncover the opening through the window. A plurality of the control latches 39 is mounted on a suitable shaft device 40 appropriately mounted in the cabinet work and being provided with a spring 41 normally pressing the several latches into engaging position with the respective drop shutters 38. The release of the latch shaft 40 is effected by a striker 42, Fig. 3, fixed on the shutter cable 34 and designed to engage a strike 43 fixed on the rock-shaft 40. Therefore when the trap-box 24 30 is released by its electrical control and as the lower shutter 33 is pulled up by the cable 34 the trip device 42—43 is actuated so as to release all of the drop shutters 38 throughout the bank room.

As the several drop shutters 38 descend they engage respective latches 44 which normally retain self-closing lids 45 of the cash boxes 46 so that these lids are released and instantly closed for the protection of the contents of the cash boxes, the closed lids being caught by spring locks. 40

The main circuit wire 17 is provided with an extension 17' leading to an audible and visible signal device arranged preferably exterior of the banking room or at any other desired location for making an attraction signal to the public 50 or other interested individuals. The signal device 47 has an electric connection 48 leading to circuit closing switch 49 which is operative by and upon the descent of any drop shutter 38, the wiring system including a control switch 49 for 55 each such shutter connected to the circuit line 48 of the signal device or in any other appropriate manner.

From the above it will be seen that the system includes, in combination, a plurality of relative, 60 cooperative cashier safety devices with means to entrap a potential robber and with means for effecting a closure at such of the bank entrances as may be open, and further will effectuate the operation of an alarm signal device. Further 65 means are provided to protect the money which

may be in several of the cashiers' money boxes at the various windows by concurrent action of several box cover release means.

In many bank rooms and other places handling 5 money or instruments of considerable value and especially in jewelry stores it is the custom to provide a convenient vault V, Fig. 5. In such instances the vault may be provided with one of the automatic safety doors 5 and its operative mechanism as above described. The control circuit 10 of the vault door joins the main circuit wire 17—18 and is therefore under the instant control by any of the switches or circuit closers incorporated in the system; the circuit controller 14', Fig. 2, being that which controls the safety door of the 15 vault V.

At each of the cashier's windows there is provided a foot operated switch or circuit closer 19' connected to the control system lines 17—18 so that the guard may be made effective either 20 by the hand devices 19 or by the foot devices 19'.

It is understood that the several sliding elements forming window closures will have appropriate guides in the cabinet work and will be automatically latched or locked in their effective, 25 closed position.

What is claimed is:

1. In apparatus of the class described; an overhead trap and a cashier's cage structure, the latter including a counter and its front window 30 wall, a cabinet in front of the wall and overhanging a patron's standing zone in front of the counter and forming a concealed chamber, and said trap consisting of a vertical box, closed at all sides and its top, slidably concealed in 35 said chamber and having a frangible bottom closure, and control means to release the box to fall to a trapping position over said zone to enclose a potential robber at the counter.

2. In apparatus of the class described; an overhead trap and a cashier's cage structure, the latter including a counter and its front window wall, a cabinet in front of the wall and overhanging a patron's standing zone in front of the 40 counter and forming a concealed chamber, and said trap consisting of a vertical box closed at all sides and at its top and slidably concealed in 45 said chamber and having a bottom closure, and control means to release the box to fall over said zone.

3. In apparatus of the class described; an overhead trap and a cashier's cage structure, the latter including a counter and its front window wall, a cabinet in front of the wall and overhanging a patron's standing zone in front of the 50 counter and providing a concealed chamber, said trap consisting of a vertical box concealed in said chamber and having a bottom adapted for the admission of the body of an individual standing 55 on said zone when the box descends, control means to release the box for descent over the said zone, and a key-controlled means for locking the box in its lower position.

JAMES M. CORDRAY.
